UNITED STATES PATENT OFFICE.

HERBERT S. BUSEY, OF WORCESTER, MASSACHUSETTS, ASSIGNOR TO THE AMERICAN STEEL AND WIRE COMPANY OF NEW JERSEY, A CORPORATION OF NEW JERSEY.

WIRE-DRAWING BENCH.

Application filed April 8, 1925. Serial No. 21,495.

This invention relates to wire drawing apparatus and more particularly to a novel construction of wire drawing bench especially adapted for drawing wire by the continuous method.

The principal object of this invention is to provide a bench having a plurality of dies and drawing blocks for successively reducing or drawing down the wire, and having means for automatically lubricating the wire as it enters the dies and again while on the blocks.

Another object is to provide an automatic lubricating system for wire drawing benches, which will provide a continuous recirculation of the lubricating fluid.

A further object is to provide a wire drawing bench having the novel construction, combination and design of parts hereinafter described and illustrated in the accompanying drawings.

In the drawings, Figure 1 is a side elevation of a wire drawing bench embodying my invention.

Figure 2 is an enlarged fragmentary sectional elevation of the bench through a portion of the trough and one of the die holders.

Figure 3 is an enlarged transverse section on the line IV—IV of Figure 2.

Referring more particularly to the drawings, the letter A designates the bench as a whole, which consists of the usual base 2 and top 3. The working side of the bench is provided with an overhanging trough 4 adapted to contain lubricant.

The trough 4 is provided with a plurality of substantially equally spaced openings 5 through its bottom wall and a plurality of hollow die holders 6 are secured to the bottom wall of the trough so that their hollow interiors align with said openings. The upper ends of said die holders are provided with a die holding portion 7 adapted to hold a die 8, and an inclined back wall 9 arranged to the rear of the dies which is provided with outlet openings 10. The openings 10 are inclined toward the rear or entering face of the die 8. A pair of side wings or flanges 11 are provided at the upper end of the die holder and extend above the upper end of said back wall 9, forming a recess or well.

Suitable horizontal drawing blocks 12 are journaled in suitable bearings 14 on the top

3 of the bench A, and have their wire receiving portions or drum overhanging the trough 4. The drawing blocks 12 alternate with all of the die holders 6, with the exception of the last or foremost die holder 6, so as to draw the wire through the dies 8. A vertical take-up block 12^a is journaled in bearings 14^a on bracket 15 at the forward end of the bench to draw the wire through the foremost die 8 and form the drawn wire into a suitable bundle.

The drawing blocks 12 are each operatively connected to suitable independent motors 16 mounted on the top of the bench A, and the take-up block 12^a operatively connected through gearing 17 and shaft 17^a to a motor 16^a mounted on a bracket 16^b extending outwardly from the forward end of the bench.

A suitable lubricant outlet conduit 18 extends forwardly from an outlet opening 19 in the side wall of each of the die holders 6 and terminates in a vertically disposed nozzle 20 under the drawing blocks 12.

A suitable lubricant supply conduit 22 extends longitudinally of the bench A under the trough 4 and is connected to each of the hollow die holders 6 by branches 23, which are provided with valves 24 for controlling the flow of lubricant into the die holders 6.

The conduit 22 is connected by a branch 25 intermediate its ends to the outlet of a circulating pump 26 which has its inlet connected by a conduit 27 with the trough 4.

In operation, a quantity of lubricant is supplied in the trough 4 and the pump 26 is operated to draw the lubricant from the trough 4 and force it through the conduit 22 and branches 23 into the hollow die holders 6, from which it is ejected through the outlet openings 10 and nozzle 20 so as to spray and contact with the entering side of the dies 8 and under side of the drawing blocks 12, thereby thoroughly lubricating the wire as it enters said dies and as it is wrapped on the blocks. The recess or well formed in the upper end of the die holders 6 to the rear of the dies 8, due to the location of the side flanges 11, causes the lubricant to flow back along the wire entering the dies 8 and thus further lubricates the wire. The excess lubricant flows back into the trough 4 and is constantly recirculated, thus

causing a material saving in lubricant and preventing the escape of lubricant onto the other parts of the bench and floor as is now common.

5. While I have shown and described only one specific embodiment of my invention, it will be expressly understood that I do not wish to be limited thereto, since various modifications may be made without departing from the scope of my invention as defined in the appended claims.

I claim—

1. The combination with a wire drawing bench, of a hollow die holder having a die secured thereon, a drawing block for pulling the wire through said die, means for forcing lubricant up through said hollow die holder, and outlets from said die holder adapted to direct said lubricant upwardly 20 against the entering side of said die and the face of said block.

2. The combination with a wire drawing bench, of a hollow die holder having a die secured thereon, a drawing block for pulling the wire through said die, an outlet opening in the upper end of said die holder, a conduit extending outwardly from the side of said die holder and terminating in a nozzle at a point beneath said block, a trough extending under said die holder and block, means for forcing a flow of lubricating liquid through said hollow die holder so as to discharge through said outlet opening and conduit and contact, respectively, with the entering face of said die and the underside of said block, said lubricant being adapted to flow back into said trough, and means for recirculating said lubricant from said trough through said hollow die holder.

In testimony whereof, I have hereunto signed my name.

HERBERT S. BUSEY.
